UNITED STATES PATENT OFFICE.

WILLIAM F. BOCKHOFF, OF RICHMOND, INDIANA, ASSIGNOR TO NATIONAL AUTOMATIC TOOL COMPANY, OF RICHMOND, INDIANA, A CORPORATION OF INDIANA.

ADJUSTABLE ARM FOR MULTISPINDLE DRILLS.

1,360,081.

Specification of Letters Patent. Patented Nov. 23, 1920.

Application filed February 20, 1918. Serial No. 218,346.

To all whom it may concern:

Be it known that I, WILLIAM F. BOCKHOFF, a citizen of the United States, residing at Richmond, in the county of Wayne 5 and State of Indiana, have invented a new and useful Adjustable Arm for Multispindle Drills, of which the following is a specification.

In multi-spindle drills, the rotatable drill 10 carrying spindles are each mounted upon an adjustable arm, or other adjustable carrier, in such manner as to be not only laterally adjustable throughout a considerable area, but also such as to be vertically adjustable 15 in order that drills of different lengths may be accommodated and also in order that holes of different depths may be produced by a single feeding action of the work-supporting table or the main head 20 carrying all the spindles.

The space within which vertical adjustment may be accomplished and within which the adjusting mechanism may be adjusted, is comparatively limited and yet the adjusting mechanism must be repeatedly manipulated during any working period.

The object of my present invention is, therefore, to produce an efficient adjusting mechanism, by means of which the vertical 30 position of a drill-carrying spindle may be attained, of such character as to be efficient at all times and readily manipulated.

The accompanying drawings illustrate my invention. Figure 1 is a side elevation, in 35 partial vertical section, of an apparatus embodying my invention; Fig. 2 is a plan.

In the drawings, 10 indicates the spindle-carrying arm which is supported on the usual support 11, by means of the clamping bolt 12. This arm 10 comprises a pair of parallel sides, as indicated in Fig. 2, between which the bolt 12 may extend, and a somewhat vertically extended head 13, which comprises a vertical cross plate 14 bridging 45 the space between the two side pieces. The forward or end face of this plate 14 forms a support and guide for the vertically adjustable spindle head 15 which carries a pair of rearwardly projecting threaded pins 16, 50 16 which pass through vertical slots 17, 17 formed through plate 14. On the threaded portion of each screw 16 is a clamping nut 18. The rear face of plate 14 is smooth and preferably parallel with the forward face 55 and slidably mounted upon this face be-

tween the two bolts 16, is a friction clamping shoe 19 adapted to be engaged by lever 20, the ends of which are bifurcated and straddled over the bolts 16 beneath the nuts 18. The adjacent faces of shoe 19 and lever 60 20 are so formed that the lever 20 may rock upon the shoe 19 and, in the form shown in the drawings, the shoe is shown as tapered toward each end from the middle so as to form a central peak 21 upon which the 65 lever 20 may rock.

These two parts 19 and 20 may be conveniently formed of material which may be hardened so that there will be no crushing of contacting points under pressure exerted 70 by the nuts 18. The forward or friction face of shoe 19 is preferably smooth so as to slide freely upon the rear face of plate 14 but it will be readily understood that these two contacting faces may be roughened 75 or serrated, if desired.

In assembling the parts, the upper one of nuts 18 will be set to desired position where it forms an adequate abutment for the upper end of lever 20. By tightening 80 the lower nut 18, lever 20 will exert a uniform pressure upon shoe 19 and a consequent uniform pull upon both of the bolts 16 so as to firmly and uniformly clamp the spindle head 15 upon the forward face of plate 14. 85 A loosening of the lower nut 18 only will serve to free the spindle head 15 so that it may be readily vertically adjusted.

By providing the shoe 19, I distribute, over a considerable area, the clamping pressure exerted by lever 20 so that the rear face of plate 14 is not marred and, consequently, so that there is no tendency toward production of valleys in the rear face of plate 14, and a consequent interference with ready 95 and accurate adjustment.

I claim as my invention:

1. The combination, with a member having a receiving plate, of an adjustable member slidably mounted on said plate, two 100 bolts carried by said spindle and projecting through the plate, a clamping nut mounted on each bolt, a friction shoe between the bolts and movable therewith and arranged to engage the plate, and a lever 105 extended between the two clamping nuts and having a rocking engagement with the friction shoe.

2. The combination, with a member hav-

ing a receiving plate, of a head slidably mounted on said plate, a friction shoe arranged to engage the plate in opposition to the slideable head and movable therewith, a 5 lever having a rocking engagement with the friction shoe, an abutment carried by the adjustable head and engaging one end of said lever, and an adjustable abutment carried by the adjustable head and arranged to

engage the opposite end of said lever vari- 10 ably.

In witness whereof, I WILLIAM F. BOCKHOFF have hereunto set my hand at Richmond, Indiana, this 18th day of February, A. D. one thousand nine hundred and eighteen. 15

WILLIAM F. BOCKHOFF.
